(57) **CLAIM**

The ornamental design for a knife blade, as shown and described.

DESCRIPTION

Fig. 1.1 is a side view of a knife blade showing our new design.

Fig. 1.2 is a bottom perspective view thereof;

Fig. 1.3 is a top perspective view thereof;

Fig. 1.4 is a top view thereof;

Fig. 1.5 is a front view thereof.

The broken lines in the drawings are for showing portions of a knife blade that form no part of the claimed design.

1 Claim, 5 Drawing Sheets(56)
